UNITED STATES PATENT OFFICE.

EUGENE SCHNEIDER, OF PARIS, FRANCE, ASSIGNOR TO SCHNEIDER & CIE., OF PARIS, FRANCE, A LIMITED JOINT STOCK COMPANY OF FRANCE, AND JOSEPH LOUIS ROUTIN, OF PARIS, FRANCE.

APPARATUS FOR CONTROLLING FIRING ON BOARD WARSHIPS.

Application filed January 5, 1922. Serial No. 527,277.

To all whom it may concern:

Be it known that I, EUGÈNE SCHNEIDER, a citizen of the Republic of France, residing at 42 Rue d'Anjou, Paris, France, have invented new and useful Improvements in Apparatus for Controlling Firing on Board Warships, which is fully set forth in the following specification.

This invention has for its object to provide an improved apparatus for controlling gun fire on board warships irrespective of the nature of the target but more particularly with relation to aerial targets.

In my U. S. application Sr. No. 527,275, filed Jan. 5, 1922, there is described an apparatus for controlling the firing on land against aerial targets. This apparatus which is hereinafter referred to by the expression "corrector" comprises means for continuously indicating, at points adjacent a gun, or guns, the proper angles of train and elevation to which the gun must be laid in order that a particular target may be destroyed when the gun is fired. The apparatus is such that no sighting telescopes are required at the gun, it being only necessary, in order for the training and elevating pointers to properly perform their duties, to train and elevate the gun to such a position that the needles of an angle of train voltmeter and an angle of elevation voltmeter are brought to predetermined positions, i. e., "zero" position. The apparatus automatically transmits readings corrected for the zenithal and azimuthal speeds of the target, range and windage. The corrector also transmits fuse settings which makes it necessary to maintain a regular rate of fire in order that the projectiles may be fired at the exact moment corresponding to the mechanical predetermination of the value of the fuse settings.

In my copending application, Sr. No. 527,276, filed Jan. 5, 1922, there is described an apparatus for automatically and continuously correcting the training of guns, mounted on board a vessel, in accordance with the inclinations of the trunnions of said guns produced by the pitching of the vessel. This apparatus comprises a gyroscope which controls a movable member,

means being interposed between said gyroscope and member for moving the latter through an angular distance proportional to the product of the angle of inclination, relative to a horizontal plane, of the trunnions of said guns and the tangent of the angle of elevation of the guns.

The present invention is preferably employed in combination with the corrector and apparatus for correcting the angle of train in accordance with the inclination of the gun trunnions. It may, however, be employed in combination with any other suitable "follow the pointer" system.

When the fire control apparatus forming the subject-matter of this invention is employed in combination with the apparatus described in my two applications referred to above, it allows of:

1. Employing on board warships, notwithstanding their rolling and pitching motion, "correctors" of the kind described in the aforesaid application.

2. Regulating the rhythm of the firing in accordance with the rhythm of the "correctors."

3. Where the firing takes place when reaching proper elevation, "correcting" the deviation due to the angular displacement of the gun barrel during the time which lapses between the firing of the gun and the instant when the projectile leaves the gun barrel.

4. Effecting automatically in a continuous manner the correction of the aiming necessitated by the inclination of the gun trunnions.

The invention consists essentially in the combination of a "corrector" mounted on a gyroscopic support, with gun barrels provided each on the one hand with a gyroscopic device for effecting automatically the firing of the gun at the moment when the axis of the gun barrel encloses with the horizon the proper angle determined by the "corrector", and on the other hand with a device for effecting an automatic and continuous compensation for the deviation due to the inclination of the gun trunnions.

It has already been proposed to employ certain devices for the automatic firing of

a gun at the moment when the axis of the gun barrel encloses the proper angle with the horizon; according to the present invention a known device of this kind is placed under the control of an electric firing switch which forms part of the "corrector." In order that the firing shall have the greatest possible intensity, it is important to aim continuously and to fire as exactly as possible with the frequency compelled by the use of the "corrector", and which, if t_s is the number of seconds that are necessary for setting the fuse and loading the gun, will be

$$15 \quad \frac{60}{t_s}$$

shots per minute. For this purpose, therefore, it is advisable not only to connect the special switch with which the "corrector" is fitted, in series with the corresponding automatic switch of each gun, in such a manner that the firing can only be effected when the two switches are closed simultaneously, but also to provide on the gun a mechanism actuated by a gun server who is specially appointed to control the firing. The function of this gun server is to maintain the gun barrel in the immediate vicinity of the position corresponding to automatic firing in order that he can release the firing mechanism as soon as he shall have been notified by an optical or an acoustic signal of the circumstance when the switch of the "corrector" has just been closed temporarily, because in order that the fuse setting shall remain practically utilizable this closing of the switch cannot be maintained for longer than one to two seconds as a maximum.

40 When the firing is controlled, as above stated, the deviation in elevation due to the absolute angular velocity of the gun barrel in its rocking movements, may be rendered negligible by utilizing in the proper manner the mechanism which is actuated by the gun server appointed to control the firing. For this purpose it is sufficient to limit to a very small amount the absolute angular velocity of the gun barrel in space at the moment of the projectile leaving the gun.

50 When the duration T of one oscillation of the ship is greater than t_s , the apparatus forming the subject matter of the present invention may also be employed by imparting to the "corrector" for the rhythm of the firing, a periodic rhythm adjusted to the frequency of the oscillations of the ship, and controlling the firing in an entirely automatic manner.

60 The gun being assumed to be handled in such a manner as to enclose constantly with a line of origin marked on its carriage, the angle of inclination i transmitted by the "corrector" the firing must then take place at the instant when the line of origin marked

on the gun carriage encloses with the horizon an angle equal to

$$i + u \frac{(dr)}{(dt)_1}$$

70 the correction

$$u \frac{(dr)}{(dt)_1}$$

75 being the variation of the angle of rolling r during the constant time u which lapses between the firing and the instant when the projectile leaves the gun barrel.

Now if R is the maximum amplitude of the rolling motion I get the equation

$$80 \quad r = R \sin \frac{\pi t}{T} \text{ and } u \frac{(dr)}{(dt)_1} = u 2 \frac{\pi}{T} R \cos \frac{2\pi t}{T}$$

85 It will thus be perceived that the correction to be made is proportional to the maximum amplitude R of the rolling motion. In order to make the necessary advance in the firing it will then be sufficient to get automatically the measure of R for each oscillation of the ship, and to shift the firing pointer, always automatically and proportionately to the value thus found.

90 The obtaining of this result is one of the essential characteristic features of this invention.

95 Figs. 1 and 2 are diagrammatic figures illustrating the "corrector" combined with a gyroscopic support similar to that employed in the aforesaid apparatus for correcting the angle of train of the guns in accordance with the inclination of the gun trunnions.

100 Fig. 3 is a diagrammatic figure illustrating one of the devices that may be used for assuring an automatic firing when the gun has been caused, at the proper time, through the intervention of the gun server specially appointed for this work, to enclose with the horizon the angle that has been calculated mechanically by the "corrector" and transmitted in a continuous manner to the said apparatus.

105 Fig. 4 shows a detail of Fig. 3.

110 Fig. 5 illustrates the apparatus for giving automatically the correction

$$115 \quad u \frac{(dr)}{(dt)_1}$$

120 which must be taken into consideration when firing by passing through proper elevation.

125 In Figs. 1 and 2 which are two elevations illustrating respectively the front elevation and the side elevation of the "corrector" mounted on a gyroscopic support, 1 is a casing containing a gyroscope with vertical axis, whose rotation is maintained for instance by means of an electric motor. This casing is suspended by means of a Cardan joint around two axes 2 and 3 at right angles to each other, from the fork 4 which serves

130

as a support to it, and is mounted on the deck of the ship. This suspension is so constructed as to produce neutral equilibrium. 5 is a casing containing all the parts of the "corrector" and it is mounted on 1 in such a manner as to be capable of being trained relatively to the latter. 6 is a ring suspended from the lower part of 5 by four arms 7; it is designed to balance the combination 1, 5, 6, 7 relatively to the suspensory arrangement.

8 and 9 are two spirit levels employed for correcting the small deviations due to the precession of the gyroscope. For this purpose two gun servers exert temporarily upon the member 10 a couple at right angles to the movement which must be made in order to bring back the spirit level bubbles between their marks. 11 and 12 are the two telescopes of the "corrector"; their eye pieces are fitted with very supple rubber fittings 13 and 14 in order to prevent the gun servers from exerting a disturbing action upon the equilibrium of the apparatus. With the same object the different parts for manoeuvring the "corrector" are to be actuated by means of very supple flexible shafts or preferably by means of small electric motors mounted on the "corrector" casing.

15 is a circular rail composed of steel tubing intended to afford a point of support for the gun aimers and the operators of the apparatus, and upon which may be mounted the handles for controlling the flexible shafts or parts controlling the electrical motors acting upon the "corrector". This rail is fixed in one direction to the fork 4, and in the other direction to the fork 16, that is fixed to 4.

Instead of adjusting the horizontal direction of the casing 5 relatively to 1, it is obvious that it can be moved by rotating the fork 4 relatively to the axis of its support, by merely shifting 5 relatively to 1 through the angle of drift or deviation.

The "correctors" intended to be mounted upon gyroscopic supports must be so constructed that the centre of gravity of each rotating part will be situated in the axis of rotation.

In the diagrammatic Fig. 3 it has been assumed that the transmission of the angle of inclination to be given to the gun barrel was effected by utilizing the known principle of the Wheatstone bridge. 17 and 18 are two rheostats arranged in the form of an arc of a circle and located on the "corrector" and the gun carriage respectively.

19 is a storage battery feeding 17 and 18: 20 and 21 are two movable contacts connected in series by a circuit that includes a voltmeter 22. The contact 20 is moved automatically by the "corrector" through an angle proportional to the inclination to be given to the gun barrel. The contact 21,

fixed to a worm wheel 23, is kept constantly vertical by means of a gyroscopic device shown in detail in Fig. 4. The rheostat 18 is carried by a wheel 24 mounted loose on the shaft of the gyroscope, and upon which 70 shaft there is said worm wheel 23. 25 is a worm meshing with worm wheel 23 and journalled in two bearings 26 and 27 mounted upon 24. This worm is actuated by means of a hand crank 28.

The orders transmitted by the "corrector" are executed by the elevating gun server whose duty is to move 18 and consequently 24 relatively to 21, by acting upon 28 in such a manner that the pointer of the 80 voltmeter 22 shall be constantly maintained at zero.

The gyroscopic device situated near the gun barrel, is mounted on the gun carriage in such a manner that the wheel 24, like the 85 whole composed of the parts shown in Fig. 3, will remain constantly in planes parallel to the plane of the firing.

29 represents the projection of the axis of one of the trunnions of the gun barrel 90 or of the gun cradle. 30 is a toothed sector fixed to the trunnions 29, meshing with a worm 31 journalled in two bearings fixed to the gun carriage; this sector is rotated by means of the hand crank 32.

33 is a leaf spring arranged along one of the radii of the sector 30 and electrically insulated from the latter; 34 is a pointer carried by a parallel motion 35-36-37-38 jointed at 35 on an axle pin fixed to the 100 gun carriage, at 37 on an axle pin fixed to the wheel 24, and at 38 on the centre of the wheel 24.

The shaft 35 being mounted on the straight line joining 29 to 38, and the 105 three distances between 37 and 38, 36 and 35, 29 and 34 being equal, it will be perceived that 34 will describe a circle around 29 by moving, like the wheel 24, through angles that are proportional to the inclination to be given to the gun barrel.

39 is a rotary interrupter driven by clock work; it forms part of the "corrector". Its speed of rotation, determined by the herein-before explained considerations, is

$$\frac{60}{t_s}$$

revolutions per minute (t_s , being the number of seconds required for setting the fuse 120 and loading the gun).

The development of the rotary sector that assures the contact and the connections of the interrupter with the other members of the "corrector", are such that contact will 125 be established automatically one second before the exact instant when the firing should be effected theoretically, and is broken only one second after the said instant.

40 is an electric lamp which receives cur- 130

rent from the battery 19 during the entire period when 39 remains closed. 41 is an electro-magnet which produces the firing and comes into operation only on condition that 33 shall be brought into contact with 34 whilst 39 is closed.

The duty of the gun server appointed to control the firing, consists on the one hand in maintaining constantly by the operation 10 of the crank handle 32, the spring 33 in the immediate vicinity of 34, and on the other hand of placing 33 into contact with 34 each time the lamp 40 lights up, taking care, as regards this last operation, to proceed 15 without abruptness so as to reduce to a minimum the absolute angular velocity of the gun barrel in space at the instant of firing the shot.

In Fig. 4 which illustrates the details of 20 the mounting of the wheels 23 and 24 and of the parts carried by them, 42 is a casing containing a gyroscope with vertical axis whose motion is maintained for instance by means of an electric motor. This casing is 25 suspended in neutral equilibrium around two axle pins 43 and 44 at right angles to each other from the fork 45 which serves it as a support and which is fixed to the gun carriage in such a manner that 44 will be 30 parallel to the axis of the gun barrel trunnions. 46 is a spirit level mounted on the casing 42; it is employed for maintaining the axle pin 43 horizontal.

In Fig. 5 which illustrates diagrammatically by way of example the manner in 35 which may be constructed the apparatus for giving automatically the correction

$$u \frac{(dr)}{(dt)_1}$$

40 which must be taken into consideration when firing by passing through proper elevation, that is, when firing "on the roll," 47 is a supporting plate fixed to the gun carriage 45 parallel to the plane of the firing. 48 is a shaft mounted on 47 and around which a toothed wheel 49, fixed to a ratchet wheel 50, is capable of rotating freely. 51 is a pawl which is capable of rotating around 50 an axle pin 52 and which a returning spring 53 has a constant tendency to keep bearing against 50. 54 is a lever fixed to 49, and which a returning spring has a tendency to keep bearing against a stop 56. 57 and 58 55 are two shafts fixed on 47; around them is adapted to rock the jointed parallelogram 57-58-59-60. 61 is a pinion fixed to the lever 57-59. 62 is a gearing pinion for imparting to 49 a rotational motion in the 60 same direction as that of 61 but reduced to a suitable ratio. 63 is a stop rod fixed to the lever 59-60. 64 is a lever fixed to 49; it carries at its end an insulated metal strip 65 which shares all the movements of the 66 gun carriage. 66 is a rod which carries a

second insulated metal strip 67, and which is connected to a gyroscopic apparatus in such a manner that the line uniting 48 to 66 will be constantly directed along the vertical.

70

68 is a lever fixed to 51 and arranged in such a manner as to move 51 away from 50 when 68 strikes 66. The firing is effected automatically by the closing of an electric circuit each time the movable contact 65 in 75 rotating in the direction of the arrow meets the contact 67.

75

It is easy to prove that at the moment when the firing takes place the contact 65 will have been shifted in advance through 80 an angle proportionate to the maximum amplitude of the rolling motion of the ship thereby allowing of effecting automatically the correction of the determined deviation, as hereinbefore stated. Namely, if we consider what has taken place between the half period that has preceded this contact, it will be perceived that when the plate 47 in rotating in the opposite direction to that of the arrow (Fig. 5) has passed through the 85 vertical position, 63 having been arrested against 66, the parallelogram 57-58-59-60 has become deformed and the pinion 61 is thus rotated in the direction of the arrow relatively to 47, through an angle 90 equal to R, thereby producing a proportional displacement of 65 in the same direction around 48.

90

95 As the rocking motion continues, the plate 47 is moved back again in the direction of the arrow whilst the displacement of 65 was maintained by the pawl 51, and the firing has thus been effected with the requisite advance.

100

105 Immediately after contact has been made between 65 and 67, the lever 68 strikes 66, which action, by moving 51 temporarily away from 50, allows the spring 55 to return 110 54 on to 56 so that 65 will have been brought into the position which this member should occupy in order that the same series of effects shall be able to be repeated on the next oscillation.

110

115 The improved apparatus just hereinbefore described produces only one fire for each complete oscillation. It is, however, obvious that this firing can be produced in an ascending or descending period according as to whether the apparatus is mounted on the gun carriage to the left or to the right 120 of the gun barrel (assuming the latter to be viewed from the bridge end). It is then very easy to fire two shots for every complete oscillation by employing two identically similar apparatus mounted on either 125 side of the gun barrel, and connecting in parallel the circuits of their electric interrupters.

125

130 In the case where the target is not an aerial target, the sighting station which

transmits to the guns the indications of heel and of elevation, is not necessarily mounted on a gyroscopic support. This station may then be established by utilizing known devices on the condition that it shall be completed by a mechanism that allows of determining and transmitting to the guns the correction of the deviation due to the inclination of the gun trunnions.

10 The hereinbefore described two methods of firing are still applicable to this case but it is preferable to employ the firing when reaching proper elevation and it is to be noted that in such a case the automatic 15 "corrector" illustrated in Fig. 5 may have considerable importance because with guns of large calibre the deviation

$$20 \quad u \frac{(dr)}{(dt)_1}$$

may reach and even exceed the magnitude of one degree.

Having now particularly described and ascertained the nature of my said invention 25 and in what manner the same is to be performed, I declare that what I claim is:—

1. Ordnance apparatus comprising, in combination with a gun, a corrector for transmitting angles of train and elevation to 30 said gun, and means for correcting the angle of train of the gun in accordance with the angle of inclination of the trunnions of the same, a parallelogram mounted adjacent to said gun, a contact for the firing circuit of 35 the gun operatively connected to said parallelogram for actuation thereby, a second contact for completing said firing circuit when engaged by said first named contact, and a gyroscope for controlling the movement to be imparted to said first named contact by said parallelogram.

2. An apparatus for controlling gun fire on board ship comprising, in combination with a corrector, stabilizing means positioned adjacent one of the guns to be controlled, a jointed parallelogram, an element 45 operatively connected with said parallelogram and controlled by said stabilizing means, and a contact element operatively connected with the carriage of said gun.

3. A firing mechanism for guns comprising, in combination with a gun, a firing circuit, stabilizing means positioned adjacent said gun, means including a jointed parallelogram maintained in a plane parallel to the 50 plane of fire of said gun and having operative engagement with said stabilizing means, and a contact for closing said circuit operatively connected to said parallelogram.

4. A firing mechanism for a gun comprising a plate secured to the carriage of said gun, a plurality of gear wheels rotatably mounted on said plate, means for rotating said gears through an angular distance proportional to the angle of roll of the ship on

which said mechanism is mounted, a stabilizer for controlling the movement of said means, a contact member secured to said stabilizer, and a second contact member operatively connected to one of said gears. 70

5. A device of the class described comprising, a stabilizer positioned adjacent a gun, a contact point mounted on said stabilizer, a second contact point, and means including a jointed parallelogram positioned on the 75 mount of said gun operatively connected to said last-named contact point for rotating the latter through an angular distance proportional to the angle through which said gun moves between the instant of firing the 80 gun and the instant when a projectile leaves the gun barrel.

6. A device of the class described comprising, in combination with a gun and an electric circuit for firing said gun, a stabilizer, a contact controlled by said stabilizer, a movable contact, and mechanical means for automatically moving said last-named contact through an angular distance proportional to the maximum amplitude of the 85 rolling motion of a ship on which said gun is mounted.

7. Ordnance apparatus for use aboard a ship comprising, in combination, a gun, a corrector for transmitting angles of train 90 and elevation to said gun, a gyroscope for stabilizing said corrector, and firing mechanism for said gun including a jointed parallelogram, a firing contact for closing the electrical circuit of said firing mechanism 95 and adapted to be moved by said parallelogram and means for controlling the movement of said parallelogram.

8. Ordnance apparatus for use aboard a ship comprising in combination, a gun, a corrector for transmitting angles of train 100 and elevation to said gun, a support for said corrector, a gyroscope for stabilizing said support, and means for automatically firing said gun at the instant the latter reaches the 105 desired inclination including a movable contact, and means for automatically advancing said contact through an angle proportional to the angle through which the gun moves between the instant of firing the gun and 110 the instant when the projectile leaves the gun.

9. Ordnance apparatus for use on board ship comprising, in combination with one or more guns, a corrector, and means for firing 115 said gun or guns including an electric circuit breaker, a gyroscope for stabilizing one of the contacts of said circuit breaker, a parallelogram mounted for engagement with the support of said stabilized contact, a ratchet 120 mechanism and gearing for imparting the movement of said parallelogram to said ratchet mechanism, the second contact of said circuit breaker being shifted by said ratchet mechanism through an angular dis- 125 130

3
tance corresponding to the maximum amplitude of the rolling motion of the ship before each time of firing.

10. Ordnance apparatus for use on board a ship comprising, in combination, a gun, and firing means for said gun including relatively movable contacts, a gyroscope, and a parallelogram mounted adjacent said gun and cooperating with said gyroscope to position one of said contacts so that the en-

gagement of said contacts shall be effected to fire the gun when said gun is at the proper angle notwithstanding the rolling of the ship.

In testimony whereof I have signed this 15
specification.
